[57] CLAIM

The ornamental design for a baby guard for a toilet seat lid, as shown and described.

DESCRIPTION

FIG. 1 is a front elevational view of the baby guard for a toilet seat lid showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reduced scale perspective view showing the baby guard in use.

The broken line representation of a toilet in FIG. 7 is for purposes of illustration only and forms no part of the claimed design.

FIG. 1

FIG. 2

*FIG. 3**FIG. 4**FIG. 5*

FIG. 6

FIG. 7
